UNITED STATES PATENT OFFICE.

JOHN E. HARKER, OF MILFORD, IOWA.

SIGHT FOR FIREARMS.

No. 871,983.

Specification of Letters Patent.

Patented Nov. 26, 1907.

Application filed September 11, 1906. Serial No. 334,175.

To all whom it may concern:

Be it known that I, JOHN E. HARKER, a citizen of the United States, residing at Milford, in the county of Dickinson and State of Iowa, have invented a new and useful Sight for Firearms, of which the following is a specification.

My invention relates to rear detachable single barrel shot gun sights and has for its object to provide a detachable sight which can be readily attached and detached from the ordinary single barrel take down shot gun, and which presents a perfectly flat top to the sight with a groove therein for the purpose of enabling the marksman to take a better and quick sight, and to prevent cross firing.

With this object in view, my invention consists in the novel construction of the detachable sight.

Referring to the accompanying drawing: Figure 1 is a perspective view of a shot gun barrel showing rear detachable sight in position thereon. Fig. 2 is a perspective view of the detachable rear sight, and Fig. 3 is a top plan of the sight showing barrel broken away and a portion of the sight broken away.

Like numerals of reference indicate the same parts throughout the several figures in which;

1 indicates a shot gun barrel and 2 the rear detachable sight, said rear detachable sight being as shown in Fig. 2 constructed of a thin metal band having the top portion 3 formed perfectly flat, and a sighting groove 4 formed centrally in the top 3. Walls 5 cut to conform to the shape of the barrels are arranged under the top 3 for the purpose of strengthening the same and for holding the sight snugly

in position. On one side 6 of the band forming the sight is provided a spring 7 which is preferably formed integral with the band and may be suitably secured thereto if desired. This spring 7 is curved inwardly at 8 as clearly shown at Fig. 2, said spring 7 entering a notch 9 in the gun as shown in Figs. 1 and 3.

In attaching the sight the barrel is detached from the stock of the gun in the usual method and the sight is placed on the barrel raising the spring 7 and pushing same slightly forward; the barrel is then replaced on the stock and the sight is pulled back until the spring 7 drops into the notch 9 thus securely holding the sight in position and preventing accidental movement thereof.

In detaching the sight the spring 7 is raised and the sight pushed forward as before cited; the barrels are then detached from the stock and the sight is slipped off the barrels and the barrels again replaced on the stock in the usual manner.

Having thus fully described my invention what I claim as new and desire to secure by Letters Patent of the United States is—:

A detachable rear gunsight having a flat upper surface provided with a sighting groove, said sight comprising a band arranged to be passed over the end of the gun barrel, and a spring carried on said band arranged to enter a notch on the gun barrel for securely holding the sight in position, substantially as described.

In testimony whereof, I affix my signature, in presence of two witnesses.

JOHN E. HARKER.
